US0D1068518S

(12) **United States Design Patent** (10) Patent No.: **US D1,068,518 S**
Chen et al. (45) Date of Patent: ** Apr. 1, 2025

(54) **AIR FLOW SENSOR SEAL**(71) Applicant: **BIDI VAPOR, LLC**, Grant-Valkarie, FL (US)(72) Inventors: **Jiatai Chen**, Shenzhen (CN); **Shengwen Zhou**, Shenzhen (CN); **Jian He**, Shenzhen (CN)(73) Assignee: **BIDI Vapor, LLC**, Grant-Valkarie, FL (US)(**) Term: **15 Years**(21) Appl. No.: **29/873,780**(22) Filed: **Apr. 7, 2023**(51) LOC (15) Cl. **10-04**

(52) U.S. Cl.

Primary Examiner — Brett Miller*Assistant Examiner* — Mary Anne Arntzen(74) *Attorney, Agent, or Firm* — BakerHostetler(57) **CLAIM**

The ornamental design for an air flow sensor seal, as shown and described.

DESCRIPTION

FIG. 1 is a front view of an air flow sensor seal;
FIG. 2 is a rear view thereof;
FIG. 3 is a left side view thereof;
FIG. 4 is a right side view thereof;
FIG. 5 is a top view thereof;
FIG. 6 is a bottom view thereof;
FIG. 7 is a front isometric view thereof; and,
FIG. 8 is a rear isometric view thereof.

1 Claim, 4 Drawing Sheets# US D1,068,518 S
